LOCK

Allan C. Hubbell, Long Beach, Calif.

Application June 16, 1938, Serial No. 214,115

7 Claims. (Cl. 70—208)

This invention relates to locks, and has for one of its objects the production of a lock particularly adapted to automobile doors and the like, and the provision of means for rendering the handle of the lock inaccessible to inadvertent violent action or unauthorized attempts to twist off the handle from the lock.

A further object of this invention is the production of a simple and efficient means for moving the operating handle of a lock to and from an operating position for controlling the operation of the lock.

Other objects and advantages of this invention will appear throughout the following specification and claims.

In the drawings:

Figure 1 is a fragmentary view looking at the outer face of a door, showing the outside operating handle of the lock;

Figure 2 is a horizontal sectional view taken on line 2—2 of Figure 1, with the outside operating handle in a locked or inoperative position;

Figure 3 is a vertical sectional view taken on line 3—3 of Figure 2;

Figure 4 is a transverse sectional view taken on line 4—4 of Figure 3;

Figure 5 is a horizontal sectional view similar to Figure 2, with the parts in an unlocked position;

Figure 6 is a sectional view taken on line 6—6 of Figure 5; showing the clutching rod in an operative position;

Figure 7 is a fragmentary longitudinal sectional view of a handle locking mechanism showing the clutching rod in an inoperative position;

Figure 8 is a sectional view taken on line 8—8 of Figure 6;

Figure 9 is a sectional view taken on line 9—9 of Figure 6.

By referring to the drawings, it will be seen that 10 designates a section through an automobile door and the like, which carries a door handle 11. The normal operating position of the handle 11 is spaced from the outer wall 12 of the door 10, but when the handle 11 is in a locked position, it is adapted to be pushed into and become seated within the recess or socket 13 formed in the outer wall 12, as shown in Figure 2. In this way, the handle 11 cannot be accidentally swung when it is in a locked position, and cannot be forcibly swung by an unauthorized person who might attempt to break the locking handle 11.

The handle 11 is provided with an inwardly extending shank 14 which extends into the aper-

ture 15 formed in the outer wall 12. A reduced shank 16, square in cross-section, extends inwardly of the door 10 and is carried by the shank 14. This reduced shank 16 extends through the squared aperture of the usual type lock having spring mechanism for returning parts to their normal position.

A collar 24 is locked upon the inner end of the reduced shank 16 by means of a locking screw 25, and this screw extends through and works 10 in a spiral or cam slot 26 formed in the sleeve 21, within which sleeve 27 the collar 24 is mounted. The sleeve 27 has one end thereof journaled in the socket 28 formed in the inner face of the inner wall 29 of the door 10, and the opposite end 15 is journaled under the securing ring 30 carried by and secured to the lock 18. A gear 31 is formed on the sleeve 27 and meshes with a gear 32 carried by the shaft 33 of the inside handle 34. The shaft 33 extends through the inner wall 20 29, as shown in Figure 5, and the gear 32 is engaged by an over-center spring 35 serving to yieldably resist rotation of the gear past center from either side and thus prevent accidental swinging of the handle 34 from one position to 25 another. The spring 35 is anchored at one end to the lock 18, as shown at 36. The handle 11 may be moved into and out of the recess 13 by swinging the handle 34 in a selected direction and rotating the gear 32. This will in turn rotate the gear 31 and sleeve 27 causing the pin or screw 25 to travel in the slot 26 and move the shank 16 in the selected direction for drawing the handle 11 into or moving the handle 11 out of the recess 13. When the handle 11 is within 30 the recess 13, as shown in Figure 2, the latch bolt 17 may not be operated, but when the handle 11 is in the position shown in Figure 5 the latch bolt of the lock may be operated in the conventional manner, the coil spring 14a normally urging the handle 11 to a position out of the recess 13. The screw 25 carries a roller 25a which works within the slot 24 and the inner end of the slot 24 is turned abruptly to provide an abutment shoulder 26a to resist the movement of the screw 25 longitudinally of the slot when placed in the position shown in Figure 2 and slightly anchor the locking screw 25, thereby preventing the return of the parts to an unlocked position since the roller 25a must pass over the abutment shoulder 26a in order to pass longitudinally of the slot 24. This will tighten the locking device and tend to prevent road jars from loosening the parts.

The handle 11 carries a barrel lock 37 within the shank 14 thereof and this barrel lock 37 35

of the conventional type may be operated by a key 38 for moving the plunger 39 thereof inwardly or outwardly. A clutch rod 40 is slidably and rotatably mounted through the shank 16 and carries a square inner clutching head 41 which is adapted to fit in the square aperture 42 formed in the end of the sleeve 27. A coil spring 43^a is carried within the shank 14 and engages the head 43 at the opposite end of the clutch rod 40, as shown in Figure 6, normally urging the square clutching head 41 out of engagement with the aperture 42. When the plunger 39 is moved inwardly by the operation of the key 38, the plunger 39 interfits with the head 43 and the clutch rod 40 may be rotated thereby rotating the sleeve 27 in a selected direction to dispose the screw in locking engagement with the shoulder 26^a and lock the handle in the recess 13 or move the screw out of engagement with the shoulder and permit the handle 11 to move out of the recess 13 to the position shown in Figure 5. When the key 38 is removed the plunger 39 will recede within the barrel lock 37 and the clutching head 41 will be drawn into contact with the end of the shank 16. The rod 40 carries a radiating pin 44 for fitting in the notch 45 formed in the end of the shank 16 to hold the clutching head 41 in position and the rod 40 against rotation in the shank 16 when the key 38 is removed.

When a person within the automobile desires to move the handle 11 to an extended position, such as is shown in Figure 5, from the position shown in Figure 2, that is to say to move the handle 11 out of the recess 13, the handle 34 is swung so as to rotate the gear 32 in a manner to rotate the gear 31 in a clock-wise direction and cause the screw 25 to travel in the slot 24 or in a direction toward the handle 11. After the screw 25 has moved out of engagement with the shoulder 26^a it may move through slot 26 and spring 14^a will assist in forcing the handle 11 to an extended position.

When it is desired to unlock the handle 11 from outside the automobile and allow the handle to move to the extended position, shown in Figure 5, from the retracted position shown in Figure 2, the key 38 is inserted in the barrel lock 37 causing the lock to have clutching engagement with the clutch rod 40 moving the clutch rod 40 longitudinally within the shank 16 and causing the clutching head 41 to fit within the square aperture 42 in the sleeve 27. Then by rotating the key 38, the rod 40 will be rotated, thereby imparting rotation to the sleeve 27 and this will cause the screw 25 to travel within the spiral slot 24 out of engagement with the shoulder 26^a. As soon as the screw moves out of engagement with the shoulder the spring 14^a may slide the shank 16 outwardly and move the handle 11 out of the recess 13. During this movement of the shank the sleeve 27 will be turned until the screw is at the outer end of the slot 26.

When the handle 11 is to be locked and thus prevent unauthorized opening of the door, pressure is applied to the handle to shift the shank 16 inwardly and seat the handle in the recess 13. During inward movement of the shank the screw 25 travels through the slot 26 and turns the sleeve 27 until the screw reaches a point close to the inner end of the slot. The key is then fitted into the lock barrel 37 and pressure is applied to shift the rod 40 inwardly and seat its head 41 in the opening 42. The rod will then be turned to rotate sleeve 27 and seat the screw

back of shoulder 26. The shank 16 will then be securely held against outward movement and the handle retained in the recess 13.

Having described the invention, what I claim is:

1. In combination with a support having a recess formed in one face thereof, a lock carried by said support, a handle for actuating said lock, means associated with said lock for bodily moving said handle into and out of said recess, said means comprising a sleeve having a spiral guiding means, means associated with the handle and working in said spiral guiding means whereby the handle may be moved into and out of said recess as said sleeve is rotated, a gear carried by said sleeve, a second gear meshing with the first mentioned gear, a shaft supporting the second gear in offset relation with respect to the sleeve, and an operating handle engaging said shaft and located upon the opposite side of said support for moving said first mentioned handle into and out of said recess.

2. In combination with a support having a recess formed in one face thereof, a lock carried by said support, a handle for actuating said lock, means associated with said lock for bodily moving said handle into and out of said recess, said means comprising a sleeve having a spiral guiding means, means associated with the handle and working in said spiral guiding means whereby the handle may be moved into and out of said recess as said sleeve is rotated, a gear carried by said sleeve, a second gear meshing with the first mentioned gear, a shaft supporting the second gear in offset relation with respect to the sleeve, an operating handle engaging said shaft and located upon the opposite side of said support for moving said first mentioned handle into and out of said recess, and an over-center spring engaging said second mentioned gear for yieldably resisting the rotation of said second mentioned gear from one position to another position.

3. In combination with a support having a recess formed in one face thereof, a lock carried by said support, a handle for actuating said lock, means associated with said lock for bodily moving said handle into and out of said recess, said means comprising a sleeve having a spiral guiding means, means associated with the handle and working in said spiral guiding means whereby the handle may be moved into and out of said recess as said sleeve is rotated, a gear carried by said sleeve, a second gear meshing with the first mentioned gear, a shaft supporting the second gear in offset relation with respect to the sleeve, an operating handle engaging said shaft and located upon the opposite side of said support for moving said first mentioned handle into and out of said recess, an over-center spring engaging said second mentioned gear for yieldably resisting the rotation of said second mentioned gear from one position to another position, and spring means for normally urging said first mentioned handle to an extended position out of said recess.

4. In combination with a support having a recess, an operating handle adapted to be moved into and out of snug engagement with the recess, a shank carried by said handle, a latch bolt adapted to be actuated by said shank, spring means for normally urging said shank and handle to an extended position out of said recess, a sleeve rotatably mounted with respect to said shank, spiral guiding means formed in the sleeve,

a pin carried by the shank and operating in the spiral guiding means for moving said shank longitudinally of the sleeve as said sleeve is rotated, means for rotating said sleeve, said means 5 comprising a gear carried by said sleeve, a shaft arranged in offset substantially parallel relation to said sleeve, a second operating handle carried by the shaft and mounted upon the opposite side of said support with respect to said 10 first mentioned handle, a second gear carried by said shaft and meshing with the first mentioned gear for rotating the sleeve and moving said shank and first mentioned handle to and from a selected position, and means for releasably holding 15 the parts in a set position after once having been moved.

5. In combination with a support having a recess, an operating handle adapted to be moved into and out of snug engagement with the recess, 20 a shank carried by said handle, a latch bolt adapted to be actuated by said shank, spring means for normally urging said shank and handle to an extended position out of said recess, a sleeve rotatably mounted with respect to said 25 shank, spiral guiding means formed in the sleeve, a pin carried by the shank and cooperating with the spiral guiding means for moving said shank longitudinally of the sleeve as said sleeve is rotated, the spiral guiding means having means 30 for receiving said pin for holding the pin in a set position, a clutching rod mounted longitudinally of said shank and having clutching means for releasably engaging said sleeve, and a locking mechanism carried by said handle and operable 35 for engaging said clutching means for moving the clutching means into clutching engagement with the sleeve whereby the sleeve may be slightly rotated manually for releasing the pin for movement within the spiral guiding means to permit 40 said spring means to move said handle to an extended position beyond said recess.

6. In combination with a support having a recess, an operating handle adapted to be moved into and out of snug engagement with the recess, 45 a shank carried by said handle, a latch bolt adapted to be actuated by said shank, spring means for normally urging said shank and handle to an extended position out of said recess, a sleeve rotatably mounted with respect to said 50 shank, spiral guiding means formed in the sleeve, a pin carried by the shank and cooperating with the spiral guiding means for moving said shank longitudinally of the sleeve as said sleeve is rotated, the spiral guiding means having means 55 for receiving said pin for holding the pin in a set position, a clutching rod mounted longitudi-

nally of said shank and having clutching means for releasably engaging said sleeve, a locking mechanism carried by said handle and operable for engaging said clutching means for moving the clutching means into clutching engagement 5 with said sleeve whereby the sleeve may be slightly rotated manually for releasing the pin for movement within said spiral guiding means to permit said spring means to move said handle to an extended position beyond said recess, said 10 clutching means comprising a clutch rod, spring means for normally urging the clutch rod to a disengaging position, and said locking means comprising a key actuated barrel lock having means for engaging the clutch rod to rotate the 15 clutch rod as the key is rotated within said barrel lock.

7. In combination with a support having a recess, an operating handle adapted to be moved into and out of snug engagement with the recess, 20 a shank carried by said handle, a latch bolt adapted to be actuated by said shank, spring means for normally urging said shank and handle to an extended position out of said recess, a sleeve rotatably mounted with respect to said 25 shank, spiral guiding means formed in the sleeve, a pin carried by the shank and cooperating with the spiral guiding means for moving said shank longitudinally of the sleeve as said sleeve is rotated, the spiral guiding means having means 30 for receiving said pin for holding the pin in a set position, a clutching rod mounted longitudinally of said shank and having clutching means for releasably engaging said sleeve, a locking mechanism carried by said handle and operable for 35 engaging said clutching means for moving the clutching means to and from a clutching engagement with said sleeve whereby the sleeve may be slightly rotated manually for releasing the pin for movement within said spiral guiding 40 means to permit said spring means to move said handle to an extended position beyond said recess, said clutching means comprising a clutch rod, spring means for normally urging the clutch 45 rod to a disengaging position, said locking means comprising a key actuated barrel lock having means for engaging the clutching rod to rotate the clutching rod as the key is rotated within said barrel lock, the clutching means for releasably engaging said sleeve comprising a rectangular head, the sleeve having a rectangular socket 50 for receiving the head, and journal means for engaging the outer end of said sleeve and abutting the same.

ALLAN C. HUBBELL. 55
